[57] **ABSTRACT**

In a multiple cylinder Stirling engine that has higher and lower pressure gas chambers separated by pistons in each cylinder the pressure in the various cylinders is equalized by a valve assemblage to correct the effects of any leakage through the pistons. The valve assemblage causes the highest pressure portions of the cylinders to equalize at the lowest maximum cycle pressure in any cylinder.

**MULTIPLE CYLINDER STIRLING ENGINE WITH
EQUALIZED HIGH PRESSURE IN CELL
CYLINDERS**

This invention relates to a multi-cylinder double-acting Stirling cycle engine of the kind (herein called "the kind defined") in which each cylinder contains a piston which separates a low-temperature working space from a high temperature chamber in the cylinder and which separates from each other two working gas charges employed in two different working cycles, thus in the event of some working gas leaking past one of the pistons it may occur that during the working cycles of one of the working gas charges the mean effective pressure is higher than that obtained during the cycles of the other working gas charges. A higher mean pressure results a higher output from one or more of the cylinders and thus there is an uneven power distribution among the cylinders of the engine. For reasons of safety the governing of the engine total power output must be based upon the output from that one of the engine cylinders having the largest power output, and consequently an uneven power distribution will result in a decrease of the total output of the engine.

Therefore it is an object of the present invention to avoid different mean effective pressures in the separate working gas charges of an engine of the kind defined.

According to the present invention there is provided an engine of the kind defined wherein the low temperature working space of each cylinder is connected to two conduits the first one of which is provided with a non-return valve allowing flow of gas only in the direction into said working space, the second one of which is provided with a non-return valve allowing flow of gas only in the direction out from said working space, all of the said first conduits being connected to a common valve chamber provided with a plurality of valve-governed inlet openings each of which is connected to one of said second conduits receiving gas from the respective low temperature working space.

The scope of the monopoly sought is defined in the claims hereinafter, and how the invention may be put into practice is described in more detail with reference to the accompanying drawing which shows schematically in vertical section a four-cylinder, double-acting Stirling cycle engine according to the invention.

The engine shown comprises four cylinders 1-4 each accommodating a reciprocating respective piston 5-8 provided with a respective piston rod 9-12.

Each piston 5-8 divides the respective cylinder 1-4 in which it is arranged into two chambers of variable volumes - an upper chamber and a lower chamber. The upper chamber 13 of the cylinder 2 is connected with the lower chamber 14 of the cylinder 1. Similarly the upper chambers 15, 17 and 19 of the cylinders 3, 4 and 1 are connected with the lower chambers 16, 18 and 20 of the cylinders 2, 3 and 4 respectively. The connections are established through pipes and units 21-24 each including a regenerator and a cooler. The upper chambers 13, 15, 17 and 19 are heated by heating devices (not shown) and are thus kept at a high temperature level. The lower chambers 14, 16, 18, 20 are kept at a low temperature level due to the coolers in the units 21-24. The volume variations of each of the upper chambers - at the high temperature level - are synchronous with but phased 90° in advance of the vol-

ume variations of the lower chamber with which it is connected. The engine shown will contain four separate working gas charges, the separation being effected by the pistons. The working gas is hydrogen or helium at a high pressure level which during operation will vary, for example, between 225 and 175 bars.

The lower chambers 14, 16, 18, 20 are connected to a pipe 25 through a path containing a non-return valve allowing flow of gas only in the direction into the respective lower chamber. In the drawing only the non-return valve 26 between the chamber 20 and the pipe 25 has a reference numeral. The lower chambers 14, 16, 18 and 20 are also connected to individual pipes 27, 28, 29 and 30 respectively through non-return valves allowing flow of gas only in the direction out of the lower chambers. Only the valve 31 governing the passage between the chamber 20 and the pipe 30 has a reference numeral.

The pipes 25 and 27-30 are all connected to a valve assemblage 32. The said valve assemblage 32 contains a chamber 33 communicating with the pipe 25 and thus containing workings at the minimum pressure level.

The chamber 33 contains a two-armed lever 34 normally balanced by equal forces transmitted to its ends through rods 35 and 36. The rod 35 carries a two-armed lever 37 balanced by equal forces from expandible chambers 38 and 39 communicating with the pipes 27 and 28 respectively.

The ends of the lever 37 are located adjacent to valve stems of valves 40 and 41 controlling a passage between the chamber 33 and the pipes 27 and 28 respectively. If the lever 37 is angularly displaced in a vertical plane one of the valves 40 and 41 will open the connection between the respective high pressure pipe 27 or 28 and the chamber 33.

The rod 36 carries a two-armed lever 42 of the same type as the lever 37 and able to actuate valves for governing connections between the pipes 29 and 30 and the chamber 33.

The illustrated arrangement operates as follows:

During normal operation under constant load the gas pressure will vary between equal levels in the four separate working gas charges respectively contained mainly in the chambers 19-20, 13-14, 15-16 and 17-18. Therefore the non-return valves will not operate at all, and the minimum gas pressure will prevail in the pipe 25 while equal maximum pressures will prevail in the four pipes 27-30.

However, during the operation of the engine it may happen that some gas passes a piston, for example from the chamber 14 in the cylinder 1 to the chamber 19 in the same cylinder. Therefore the gas charge in the chambers 19-20 will be increased in quantity and give rise to a higher mean effective pressure and a higher maximum pressure than the other charges. Consequently the pressure in the pipe 30 will be greater than the pressure in the pipe 29 and the expandible bodies will rock the lever 42 to open the valve governing the passage between the pipe 30 and the chamber 33. Thus excess of gas in the chambers 19-20 will be discharged to the common chamber 33. It will be understood that in any case of uneven pressure in the pipes 27-30 the valve assemblage 32 will cause a decrease of the highest pressure in the pipes 27-30 until the pressure in all of them is equal to that prevailing in the pipe having the lowest maximum cycle pressure.

The levers 34, 37 and 42 are shown to be provided each with an upwardly extending middle section. Thus as the deviation from the neutral position increases there is increasing resistance against further deviation from the horizontal neutral position. Hereby opening of a valve for an excessive period is prevented. Such excessive opening would automatically cause opening of the other valves and thus an undesired short-circuiting of the pipes 27-30 and the pipe 25.

The non-return valves 31 ensuring that the maximum cycle pressure prevails in the pipes 27, 38, 29 and 30 are designed so as to allow a restricted flow of gas in both directions. This is illustrated by a restricted passage 43 parallel to the valve 31.

The reason for this design of the valves 31 is to make it possible to lower the mean effective pressure of the gas in all the four separate working gas cycle circuits (for regulating the power output of the engine) and retain the function of the pressure equalising valve assemblage 32.

What we claim is:

1. A multi-cylinder double-acting Stirling cycle engine wherein each cylinder contains a piston which separates a low-temperature working space from a high temperature chamber and which separates two working gas charges employed in two different working cycles, comprising in combination, first and second conduit means connected to the low temperature working

space of each cylinder, said first conduit means including a non-return valve allowing flow of gas only in the direction into said working space, said second conduit means including a non-return valve allowing flow of gas only in the direction out of said working space, and a common valve chamber connected to all of said first conduit means, said valve chamber having a plurality of inlets each governed by a control valve each of which is connected to an individual one of said second conduit means to pass to said first conduit means gas from said working spaces when maximum pressures are unequal in the working spaces, thereby equalizing the maximum pressure in all said working spaces.

2. An engine as defined in claim 1 including means opening each of said control valves as a function of pressure in its corresponding inlet compared with the pressure of at least one other inlet.

3. An engine as defined in claim 2 including means for operating said control valves to increase resistance as deviation from a balance of said compared pressures is increased.

4. An engine as defined in claim 1 wherein said inlet control valves include actuating means comprising levers operable by balancing the forces derived from the maximum gas pressures prevailing in different cylinders.
